(57) **CLAIM**

The ornamental design for a building scaffolding span assembly as shown and described.

DESCRIPTION

FIG. 1 is a perspective view of the building scaffolding span assembly;

FIG. 2 is a front view of the building scaffolding span assembly of FIG. 1;

FIG. 3 is a rear view of the building scaffolding span assembly of FIG. 1;

FIG. 4 is a right side view of the building scaffolding span assembly of FIG. 1;

FIG. 5 is a left side view of the building scaffolding span assembly of FIG. 1;

FIG. 6 is a top view of the building scaffolding span assembly of FIG. 1; and,

FIG. 7 is a bottom view of the building scaffolding span assembly of FIG. 1.

The broken lines illustrate portions of the design that form no part of the claim.
